UNITED STATES PATENT OFFICE.

WILLIAM B. DURGIN, OF CONCORD, NEW HAMPSHIRE.

DESIGN FOR A HANDLE FOR SPOONS, &c.

SPECIFICATION forming part of Design No. 20,674, dated April 14, 1891.

Application filed March 20, 1891. Serial No. 385,822. Term of patent 7 years.

To all whom it may concern:

Be it known that I, WILLIAM B. DURGIN, a citizen of the United States, residing at Concord, in the county of Merrimac and State of New Hampshire, have invented and produced a new and original Design for Spoons, of which the following is a specification.

Reference is to be had to the accompanying drawing, forming a part of this specification, in which the figure represents a face view of a spoon having my new design produced thereon.

The design consists of the ornamentation shown on the handle portion of the spoon and comprising the figure of a man in erect posture and attired in the costume of a Plymouth Rock colonist, the said figure being arranged in connection with minor symbols harmonizing therewith.

The letter *a* indicates the main figure mentioned, in connection with which appears, in the background, the figure *b*, representing the trunks of trees.

Along the handle of the spoon, between the main figure and the bowl of the spoon, appear figures *c*, representing sprigs of mayflower, a figure *d*, representing a pistol, a figure *e*, representing a gun, the said minor figures appearing as if entwined by a ribbon, and figure *f*, representing a skein of flax, the last-mentioned figure being formed into waves at the bowl, its end merging into the surface of the bowl.

The representation of a spinning-wheel (indicated by the letter *g*) appears at the bowl adjacent to the terminal of the figure *f*. The bowl ornamentation is, however, non-essential.

I claim—

The design for spoons, as herein shown and described.

WILLIAM B. DURGIN.
